UNITED STATES PATENT OFFICE.

WILLIAM D. WRIGHT, OF LYNCHBURG, VIRGINIA.

ADVERTISING DEVICE.

Application filed October 14, 1922. Serial No. 594,506.

To all whom it may concern:

Be it known that I, WILLIAM D. WRIGHT, a citizen of the United States, residing at Lynchburg, in the county of Campbell and State of Virginia, have invented certain new and useful Improvements in Advertising Devices, of which the following is a specification.

This invention relates to advertising devices and its primary object is to provide a simple and inexpensive but durable device which will be automatically operated to periodically display an announcement and which will be of such characteristics as to attract the attention of passers-by with certainty. Another object of the invention is to provide an advertising device which will require practically no attention from the user and which may be actuated by the force of the wind. Another object of the invention is to provide a device which may be displayed outdoors and in which the working elements will be protected from the action of the weather and which will be so supported that it will always be in operative position. Other objects of the invention will appear incidentally in the course of the following description.

The invention is illustrated in the accompanying drawings, in which—

Figure 1 is a perspective view of an advertising device embodying my invention;

Fig. 2 is a plan view, partly broken away and in horizontal section;

Fig. 3 is a view partly in longitudinal section and partly in side elevation;

Fig. 4 is an enlarged detail sectional view taken on the line 4—4 of Fig. 3;

Fig. 5 is an enlarged longitudinal section through the operating gearing;

Fig. 6 is an enlarged detail section on the line 6—6 of Fig. 2;

Figs. 7 and 8 are views similar to Figs. 2 and 3, respectively, showing another form of the invention.

In carrying out my invention, I employ a post 1 which is suitably anchored in the ground and is equipped at its upper end with a reduced portion 2 of circular cross section which constitutes a pivot post for the body 3 of the apparatus. While the device is intended more particularly for outdoor use, it obviously may be made in smaller sizes suitable for arrangement within the show window of a store and mounted upon a fixed support of any convenient

form. The body 3 of the device is given a form simulating an aeroplane and is enclosed on all sides, except for a slot 4 in its top, through which a sign or display card 5 may be periodically raised and lowered. Secured within the body and rising through the ends of the said slot 4 are channeled guides 6 which are slidably engaged by the edges of the display card or sign 5 so that the said card will be caused to move in a rectilinear path. The guides will extend above the top of the body a sufficient distance to be engaged by the sign or display member when the latter is in its extreme upper position and the height of the body will be at least equal to the vertical dimension of the display member so that, when said member is lowered, it may be completely housed within the body. The outer surfaces of the body may be decorated with stars or other insignia, as indicated at 7, or may be utilized for advertising purposes, permanent announcements being painted or otherwise placed thereon. The tail vane or rudder 8 of the device may be utilized for the same purpose. The guides 6 may be secured to the top and bottom of the body, but I prefer to secure them to frames 9 disposed transversely of the body and rigidly secured thereto, said frames serving as braces to reinforce the walls of the body and prevent collapse of the same as well as furnishing supports for the guides.

The display member may be of any desired construction and of any approved material. I prefer to form it of sheet metal having its upper edge rolled or otherwise doubled around a tube or rod 10 which has its ends fitted in the channels of the guides, this construction being shown in Fig. 6. The frames 9 are open and an operating lever 11 extends through the front frame and has its rear end connected with the lower end of the display member by a pin and slot connection, as shown at 12. The lever extends rearwardly from and forms a part of a yoke 13 which is pivoted at its front extremities to the side walls of the body, as shown at 14, and leaf springs 15 are preferably secured upon the side walls of the body to bear against the under edges of the yoke adjacent the front ends of the same whereby to assist in raising the yoke in the operation of the apparatus. The rear portions of the yoke are reinforced by a cross bar or brace 16, as will be readily understood.

upon reference to Figs. 2 and 3. The yoke passes around the supporting post 2, and cross bars 17 are secured to the sides of the body above and below the yoke and are constructed with bearings 18 to receive the post 2 and thereby rotatably support the body on the post.

Within the front end of the body, I secure a supporting structure consisting of frames 19, secured in any convenient or preferred manner to the walls of the body transversely of the same and tubular members 20 disposed longitudinally of the body and secured in the frames 19. Bushings 21 are fitted in the ends of these tubular members to provide bearings for the shafts 22 and 23 and also close the ends of the tubes so that lubricant supplied thereto cannot escape and be lost. Vertically disposed tubes 24 extend between the upper and lower tubes 20 and establish communication between the same, a reservoir or cup 25 being provided upon the upper tube to maintain a supply of lubricant and permit the same to flow readily into the upper tube. I also provide a cup or trough 26 in the bottom of the body 3, which is intended to contain a supply of lubricant, and the lower portion of the gear wheel 27, which is secured upon the shaft 23, dips into the lubricant within the said cup or trough so as to take up some of the lubricant and reduce the frictional wear between the teeth or spurs of said gear and the teeth or spurs of a pinion 28 which meshes with the said gear and is carried by the rear end of the shaft 22. The shaft 22 projects through the front end of the body 3 and is equipped with a propeller or wind wheel 29, the blades of which are so disposed that air currents flowing against the same will impart rotation to the wheel and thereby rotate the shaft 22. Obviously, the rotation of the shaft 22 will be transmitted directly to the described gearing. Upon the rear face of the gear 27 is a grooved cam 30, the groove of which is engaged by a stud or pin 31 projecting forwardly from the cross bar 16 at the center of the same. The rotation of the cam will obviously effect sliding movement of the pin or stud within the cam groove and the said pin will thus be given a reciprocatory movement in a vertical plane so that the yoke 13 and the lever 12 will be vertically oscillated. Upon reference to Fig. 4, moreover, it will be noted that the cam has a portion 32 which is nearly flat and is substantially chordal to the gear 27. This chordal portion of the cam is immediately adjacent the periphery of the gear so that it will engage the pin 31 when the pin is at its highest point. The display member or sign will, therefore, be maintained for a short period above the top of the body 3 so that the announcement thereon may be easily read.

When the device is arranged outdoors, it will, of course, be driven by the wind, and when it is displayed within a show window it may be operated by the blast from any convenient blower. Should the air currents be flowing in a direction transverse to the body of the device, they will strike the side of the tail vane 8 and will thereby swing the body around upon its pivotal support 2 so that the propeller or wind wheel 29 will be brought into the head of the wind. The said propeller will then be obviously rotated and will transmit motion to the described gearing whereby the lever 11 will be oscillated and the display member 5 will be raised and lowered at regular intervals. It will thus be seen that the operation of the device is automatic and continuous so that no attention will be required from the user except to occasionally replenish the supply of lubricant. The lubrication of the driving mechanism is thorough inasmuch as an initial supply sufficient to entirely fill the tubular members 20 and 24 as well as the cup or reservoir 25 may be initially fed into and through the said parts. The cup or trough 26 will maintain an adequate supply of lubricant for the teeth of the gears for a protracted period and this trough or cup will preferably be of such depth that it will also supply lubricant to the groove of the cam 30. My device is obviously simple and compact in the construction and arrangement of its parts and all the working parts are protected from the weather so that it may be produced and set up at a low cost and will prove durable. It constitutes a very attractive and efficient advertising device which will positively attract the attention of passers-by and will, therefore, prove a very advantageous advertising medium.

In the form of the invention shown in Figs. 7 and 8, a beveled pinion 40 is substituted for the pinion 28 on the inner end of the driving shaft, said shaft being extended through a tubular member 41 which is supported by a post 42 rising from the bottom of the body. The pinion 40 meshes with a beveled gear 43 which is secured upon a transverse shaft 44 which is housed within a tubular member 45, the housing 45 being connected with the housing 41 by a brace 46 so as to counteract any tendency of the gears to separate under strain. Oil cups 47 are provided upon both tubular members or housings for an obvious purpose. The cam 48 is provided on the outer side of the gear 43 and is operatively engaged by a pin 49 on the side of the lever 50, said lever being pivoted at its front end to a bracket 51 on the front end of the main body 1 and having a pin and slot connection at its rear end with the sign 5. The lever may be equipped with a keeper 52 to play upon the forward guide 6 and

thereby maintain proper relation of the lever to the sign, while a retractile coiled spring 53 is attached to the lever and the top of the body to aid in the upward movement thereof. A trough 54 may be provided to furnish lubricant to the groove of the cam as in the case of the trough 26, the trough 54 being indicated in dotted lines only for the sake of clearness in the showing of the other parts. It will be noted that the lever is arched at 55 so that its downward movement will not meet interference with the transverse shaft.

Having thus described the invention, what is claimed as new is:

1. An advertising device comprising a body, guides secured vertically within the body and projecting through the top of the body and a display member slidably fitted in and extending between said guides, a lever pivotally supported within the body at the front end thereof and having its rear end operatively connected with the lower end of the display member, an air-driven propeller mounted on the front end of the body, and means housed within the body and operatively connecting said propeller with said lever whereby to oscillate the lever.
2. An advertising device comprising a hollow body, a display member mounted for vertical reciprocation through the top of the body, an air-driven propeller mounted at the front end of the body, and means housed within the body operatively connecting the propeller with the display member, said means including a cam whereby the display member will be held at rest above the top of the body at intervals.
3. In an advertising device, the combination of a hollow body, a display member mounted in the body for vertical reciprocation through the top of the same, a lever pivotally mounted at its front end within the body and having its rear end operatively connected to the lower end of the display member, a pin carried by said lever, a cam engaged by said pin and having a flattened portion at its high point whereby to maintain the display member at rest for a perceptible period above the top of the body, an air-driven propeller on the front end of the body, and means housed within the body whereby said propeller will rotate said cam.
4. In an advertising device, the combination of a hollow body, a display member mounted above the body for vertical reciprocation through the top of the same, a lever fulcrumed within the body and operatively connected with said display member, a propeller shaft mounted within the body at the front end thereof and projecting through the front end of the same, an air-driven propeller secured upon the front end of said shaft, a transmission shaft arranged below the propeller shaft, tubular frame members enclosing the said shafts, tubular connections between said shafts, means for supplying lubricant to said tubular members, gearing connecting the said shafts, a cam carried by the member of said gearing on the transmission shaft, and means whereby said cam will actuate the lever.
5. In an advertising device, the combination of a hollow body, channeled guides secured in and projecting through the top of the body, a display member consisting of a rod having its ends slidably engaged in said guides, and a sheet of rigid material having its upper end fitted around the said rod, and means connected with the lower end of said sheet to reciprocate the same.

In testimony whereof I affix my signature.

WILLIAM D. WRIGHT. [L.S.]
